YARN FEEDING MEANS

Earl G. Hill, Pulaski, Va., assignor to Textile Appliance Corporation, New York, N. Y., a corporation of New York

Application March 22, 1955, Serial No. 495,923

12 Claims. (Cl. 57—90)

This invention relates to frames such as are used in the textile industry for inserting twist into continuous filament yarns, of which those made of nylon and of the material known commercially as "Dacron" are typical. More particularly, the invention is concerned with novel means for use in such frames for feeding the yarn by drawing it from the producer's package and supplying it to the bobbin, on which it is to be wound. A twisting frame equipped with the yarn feeding means of the invention may be advantageously employed for inserting a low twist into yarns supplied by the producer with zero twist as a preliminary to the operation in which the yarns are given their ultimate twist, and a frame embodying the invention and suitable for the stated purpose will, accordingly, be illustrated and described in detail.

In the processing of continuous filament yarns supplied without twist by the producer, it has been found desirable to insert the desired final twist into the yarns in stages, in the first of which the yarns are given a low twist. Such preliminary low twisting is particularly important in connection with yarns made up of fine filaments, such as those of 1 or 1½ denier, and a twist approximately $\frac{3}{4}$ turn per inch is satisfactory for the purpose. However, ring twisting frames of present construction, which operate with a spindle speed of about 7000 R. P. M. maximum, cannot insert less than about 2 turns per inch because the yarn feeding means now used cannot feed the yarn satisfactorily at the higher speed required to produce a lower twist at the stated spindle speed.

In some of the present twisting frames, the means for feeding a single yarn includes a continuously rotating bottom roll, against which the yarn is held by a floating top roll, and such a combination is objectionable, in that it must be threaded while the bottom roll is moving and also the rate of feed is likely to be non-uniform because of slippage. In an alternative construction, the feeding means at each position on the frame includes an assembly of rolls, at least one of which is driven through gearing by a continuously rotating shaft, and, while such a device may be stopped, when required, by separation of the gears, the rate of feed is limited by the speed, at which the gears can be brought into mesh. Present ring twisting frames can, accordingly, not perform the preliminary low twist operation described with the desired efficiency, because their production rate is relatively low and they insert a higher twist into the yarn than is necessary.

The present invention is directed to the provision of novel yarn feeding means for use in ring twisting frames, which overcome the disadvantages of the prior constructions. The new means for feeding a single yarn comprise a relatively large feed roll and a separator and the yarn is wrapped about the roll and separator in a plurality of convolutions, which are kept apart by the action of the separator. The feed roll is driven by a continuously rotating shaft through a clutch, of which part of the roll forms one member, and, in the event of a yarn

break, a stop motion operates to disengage the clutch and apply a brake to the roll. The roll may, accordingly, be driven at high speed but is brought quickly to rest, when necessary. Also, the long contact of the yarn with the roll insures a highly uniform feed with little or no slippage. The feeding means include other features of novelty, which will be described in detail hereafter.

For a better understanding of the invention, reference may be made to the accompanying drawings, in which:

Fig. 1 is a fragmentary front elevational view of one section of a twisting frame equipped with the yarn feeding means of the invention;

Fig. 2 is a sectional view on the line 2—2 of Fig. 1;

Fig. 3 is a top plan view of the yarn feeding means;

Figs. 4, 5, and 6 are sectional views on the lines 4—4, 5—5, and 6—6, respectively, of Fig. 3;

Fig. 7 is a longitudinal sectional view of a modified form of the feed roll of the yarn feeding means;

Fig. 8 is a plan view of a modified form of the yarn feeding means with the separator member shown in longitudinal section;

Fig. 9 is a side elevational view of the yarn feeding means of Fig. 8;

Fig. 10 is a plan view of a form of the yarn feeding means including another form of the separator member; and

Fig. 11 is a view on an enlarged scale of parts shown in Fig. 2.

The ring twisting frame illustrated in the drawings is generally of standard construction and it includes the usual end stands, of which one is shown at 20, and a number of rails, such as those shown at 21, 22, connecting the stands. A bracket 23 is attached to each stand and upper and lower pairs of rods 24 extending between the brackets carry attachments 25 clamped thereon and supporting a producer's package of the yarn Y for each position on the frame, that is, at each spindle. One such package is shown at 26 in the form of a "Dacron" cake, in which the yarn is wound on a tubular core to form a cylindrical mass. The brackets 23 have arms 27 supporting angle irons 28 running lengthwise of the frame and carrying spaced vertical rods 29, on which are mounted upper and lower rod guides 30 for the yarns being withdrawn from the respective packages. From the lower rod 30, each yarn passes to a guide 31 above a tension device 32, which is of the type including a stationary comb 33a and a movable comb 33b acted on by a spring or weight and having teeth engaging the yarn between adjacent teeth of the stationary comb. Below the tension device, the yarn engages a stationary guide 34. Guides 30, 31, and 34 may be conventional ceramic rods.

The twisting frame illustrated is provided with a device 35 for applying coating material to the strand and the device illustrated is preferred.

The device includes a driven roll 36 rotating partially immersed in a bath of the coating liquid contained in a trough 37 and a transfer roll 38 of smaller diameter, which contacts roll 36 and is engaged by the strand.

Below the coating device, the strand passes over a guide 39 and then through the faller eye 40 forming part of a conventional stop motion. The eye 40 is attached to one arm 41a of a stop motion lever 42 pivoted at 43 on a bracket 44 attached to rail 21. The lever has a second arm 41b resting upon the end of a leaf spring 45 attached to a lever 46 pivoted in the lower end of a link 47 pivotally mounted to depend from an arm 48 attached to bracket 44. Link 47 carries a latch 49 engageable with the top of a collar 50 on a vertical push rod 51, which is urged upwardly by a spring 52 bearing

at its lower end against a seat 53 on rail 22 and its upper end against a collar 54 on the rod. Rod 51 has an operating handle 55 and carries a fixed arm 56 engageable with an arm 57, which forms part of the feed mechanism.

When the yarn Y is unbroken, the passage of the yarn through eye 40 holds lever 42 in the erect position shown in Figs. 1 and 11, but, when the yarn is broken, the lever swings counter-clockwise until it is stopped by a link 58 pivoted on bracket 44 and engageable with a shoulder formed on arm 41a of the lever. In such movement of the lever, its arm 41b acts on spring 45 to rock lever 46 clockwise. A shaft 59 extending between the end stands of the frame oscillates through a small arc throughout the operation of the frame and, when lever 46 is moved clockwise by breakage of the yarn, its end moves into the path of arm 60 on shaft 59 and is pushed outwardly thereby. Such movement of arm 46 causes link 47 to swing counter-clockwise, so that latch 49 on the link is moved away from the top of collar 50 and push rod 51 is free to be raised by its spring 53. The upward movement of the push rod permits a movement of arm 57, which stops the mechanism feeding the yarn, as will be explained.

The feeding mechanism comprises a casting 61 mounted on a rail 62 and containing a bearing 63 for a shaft 64 connected through bevel gearing 65 to a continuously operating drive shaft 66. The shaft 64 carries a disc 67 of ferromagnetic material having a hub 67a pinned to the shaft and, outwardly from the disc, the shaft carries a feed roll 68 loosely mounted on the shaft and having a bearing sleeve 69 encircling the shaft. The feed roll has a closed end 70 and the disc 67 and the end section 70 of the roll serve as the elements of the clutch, by which the roll can be connected to the shaft. The roll is enclosed within a sleeve 71 having a smooth outer surface and formed with a radial flange 71a, which lies within an annular recess in one face of a ring gear 72 secured to the flange in any suitable way as by means of rivets 73.

An annulus 74 of friction material, such as cork, is secured to the outer face of the end section 70 of feed roll 68 within the sleeve 71 and the end section 70 is formed with a plurality of like recesses extending inwardly from its outer face. The recesses are equidistant from the axis of the roll 68 and equally spaced about the axis. Each recess contains a permanent magnet 75, which is cylindrical in form and has a transverse recess 75a at its outer end to form pole pieces. Each magnet also has an axial bore and is held in place against a washer 76 of cushioning material seated at the bottom of its recess by a T-bolt 77 extending through the bore and washer with its head lying in the recess 75a. The bolt extends through an opening through the bottom of the recess and carries nuts 78 bearing against the inner face of end section 70. The ends of the pole pieces of the magnets lie inward from the plane of the exposed face of the annulus 74 and, when the clutch is engaged with the face of disc 67 in contact with annulus 74, there is a small air gap between each magnet and disc 67. The width of the gap can be varied as desired by tightening the bolts 77 to adjust the position of the magnets within the recesses, such adjustment being permitted by the cushioning washers 76.

A rod 79 is mounted in seats in ears 61a on casting 61 and carries the arm 57 engaging the projection 56 on the push rod 51. A pair of arms 80 are rigidly attached to rod 79 and each arm carries a pad 81 of friction material, which is adapted to bear on the flat outer face 72a of the ring gear 72, which serves as a brake surface. One of the arms 80 has an extension 81a, to which is attached one end of a spring 82, the other end of which is connected to an eye 83 at the end of a bolt 84 threaded through an ear 61b on casting 61. The spring tends to rock rod 79 to cause the arms 80 to swing toward the brake surface 72a on gear 72 and apply the brake pads 81 thereto and the action of the spring may be adjusted by adjusting the position of bolt 84 in ear 61b. The swinging of the

rod to force the brake pads into contact with the brake surface is restricted by a stop screw 85 mounted through an ear 61c of casting 61 and engageable with extension 81a.

5 A separator roll 86 is mounted adjacent the feed roll 68 on a rod 87 having one end rigidly secured in a hollow boss 61d integral with casting 61 and the roll is provided with a gear 88 meshing with an idler gear 89. Gear 89 is freely rotatable on a rod rigidly secured in a hollow boss 61e forming part of casting 61 and meshes with gear 72. The rod 87 supports the roll 86 for rotation on an axis, which intersects the axis of rotation of feed roll 68 and lies at an angle to both vertical and horizontal planes containing the axis of roll 68. Because of the angular relation of the axis of roll 86 to that of roll 68, the teeth of gear 86 are appropriately skewed.

20 The feed roll and separator at each position of the twisting frame extend through openings in a shield 90 of channel shape, which extends lengthwise of the frame between the end stands and is supported on parts of the castings 61 at the respective positions. The shield is provided with a yarn guide 91 below each feed roll.

25 The yarn leaving guide 91 passes through a conventional pigtail guide 92 lying directly above a spindle 93, which extends through a ring in a ring rail 94 carried by a support 95 and carries a bobbin 96. The yarn from guide 92 passes to the usual traveller 97 on the ring and is twisted and wound on the bobbin by the rotation of the spindle.

30 In the operation of the frame, each yarn is drawn from its supply package 26 by the associated yarn feeding means and, for this purpose, the yarn is wound a number of times about the driven feed roll 68 and the associated separator 86. The long contract of the yarn 35 with the roll 68 causes the yarn to be drawn from the package and the skewed position of the separator causes the convolutions of yarn about the roll and separator to be kept apart, as the yarn moves lengthwise of the roll during its contact with the roll. So long as the yarn is 40 unbroken, the magnets hold the elements of the clutch engaged and the feed roll is rotated but, if the yarn breaks, the stop motion releases push rod 51 and it moves upwardly, so that the spring 82 swings rod 79 to move the brake pads 81 against the brake surface on gear 72. 45 The pressure of the pads 81 against the brake surface moves the feed roll away from disc 67 a short distance, such as $\frac{1}{16}$ ", and thus widens the air gap between the magnets and the disc, so that the force of attraction of the magnets is weakened and the brake pads can stop the feed roll. The movement of the feed roll away from the disc by the brake pads is not sufficiently great to prevent the magnets from causing the roll to move back against the disc when the pads are released from the brake surface. Also, the idler pulley 89 has so wide a 50 face that its teeth continue in mesh with those of ring gear 72 when the feed roll lies against or is spaced from the disc.

55 Whenever the feed roll is to be stopped for any reason, this can be done by swinging lever 42 counter-clockwise to move lever 46, so that its end lies in the path of arm 60 on the oscillating shaft 59. Upon the next oscillation of the shaft to swing the arm toward the lever, the lever is moved endwise and swings link 47 to free latch 49 from collar 50. The push rod 51 may then be raised by its spring 52.

60 In the yarn feeding means described, the feed roll is of relatively large diameter and the auxiliary or separator roll much smaller, as, for example, the diameter of the feed roll may be 4" and that of the separator roll 1 $\frac{1}{8}$ ". Such a combination of rolls with the separator roll positively driven has been found most satisfactory, particularly in the feeding of fine yarns without twist. For some purposes, it is satisfactory to make use of a separator roll, which is rotatable by the yarn, and this modification

is shown in Figs. 8 and 9. In the modified construction, the feed roll 68' is mounted for free rotation on a shaft 64' and it is enclosed within a sleeve 71' having a flange 71'a, the outer face of which serves as brake surface. The shaft 64' is mounted in bearings in a casting 61' and the casting is formed with a boss 61'd, in which is rigidly mounted a rod 87' supporting a separator roll 86'. Ball bearings 98 are mounted between the rod and the roll at opposite ends of the latter, so that the roll rotates freely and can be readily turned by the yarn wrapped about it. Preferably, the roll is about $\frac{3}{4}$ " in diameter between its ends. As in the construction shown in Figs. 1-7, incl., the rod 87' is mounted, so that roll 86' rotates on an axis, which intersects the axis of rotation of roll 68' and lies at an angle to both vertical and horizontal planes containing the axis of roll 68'. Roll 68' and 86' extend through openings in a shield 90'.

A third modification of the feeding means is illustrated in Fig. 10 and this construction is the same as that shown in Fig. 8 and 9, except for the separator. Like parts have, accordingly, been identified by the same reference characters in all three figures. In the construction shown in Fig. 10, the separator is a stationary guide 99, which may be of any of the usual materials employed for thread guides, such as metal or ceramic material. The guide is mounted on a stationary rod 87 and has the same relation as the separator rolls 86 and 86' to the feed roll 68'.

In the construction above described, the clutch, through which the feed roll is driven, has flat engaging surfaces on the disc 67 and the annulus 74, and the magnets are mounted in recesses in the end section of the roll. It is to be understood that the clutch could have frusto-conical engaging surfaces and the magnets could be mounted in recesses in the disc rather than in the end section of the roll. If the magnets are mounted in the disc, the end section of the roll must be made of ferro-magnetic material.

The magnetic clutch illustrated and above described is preferred, since it is simple in construction, of great durability, requires little or no attention, and needs no lubrication, so that there is no danger of lubrication smudges occurring on the yarn. For some purposes, a spring-actuated clutch may be preferred and that construction is shown in Fig. 7. Such a clutch includes a disc 100 rigidly mounted on a shaft 101, the disc and shaft corresponding, respectively, to disc 67 and shaft 64. A feed roll 102 is loosely mounted on shaft 101 and it is enclosed within a sleeve 103 having a radial flange 103a. A flat ring 104 of friction material, such as cork, is secured to the end of roll 102 in opposition to the face of disc 101. Roll 102 has a hub 102a, within which is mounted a bearing sleeve 105, and the sleeve projects beyond the hub and has one race of a ball bearing 106 rigidly secured to it adjacent its rear end. The outer race of the ball bearing is engaged by a washer 107 beneath a screw 108 threaded into the end of shaft 101. A spring 109 bears against the inner race of the ball bearing and against the hub 102a and normally holds roll 102 with the flat ring 104 against the face of disc 100, so that the roll is driven by the disc. The roll with the spring-actuated clutch described is employed in the same manner as the other feed rolls and the clutch is disengaged and the roll stopped by the mechanism employed with the construction shown in Figs. 1-7, incl., and including a rod 79 with arms 80 carrying brake pads 81 adapted to bear on the face of flange 103a.

The new yarn feeding means in any of the forms described may be threaded with the feed and separator rolls at rest and, since the feed roll is driven through a friction clutch instead of through meshing gears, there is no limitation imposed on the speed of the feed roll by the means, through which it is driven. The yarn has a long contact with the feed roll, so that there is little likelihood of slippage, and fine yarns of zero twist can be fed at the

rapid rate required with a high spindle rotation to insert a low twist, such as $\frac{1}{4}$ turn per inch, in the yarn. The feeding means thus overcomes the objections to those heretofore used.

5 I claim:

1. In a textile frame having a support for a package of a strand, strand feeding means for drawing the strand from the package, which comprises a continuously rotating shaft, a clutch element mounted on the shaft for rotation therewith, a second clutch element loose on the shaft, the elements having faces adapted to be engaged with a non-slipping contact and one of the elements being made of a ferro-magnetic material and the other carrying a permanent magnet urging the elements together with their faces in contact, an annular brake surface on the loose element, a feed roll connected concentrically to the loose element, a separator mounted adjacent the feed roll, and means for moving the elements apart including a brake shoe movable against the brake surface to move the loose element away from the element fast on the shaft and to brake the rotation of the loose element and a member for moving the brake shoe toward and away from the brake surface.
- 10 2. The strand feeding means of claim 1, in which a spring urges the member to move the brake shoe toward the brake surface and the member is held against the action of the spring by means made effective by contact with the unbroken strand and acting to release the member when the strand breaks.
- 15 3. The strand feeding means of claim 1, in which the magnet is mounted on its clutch element for movement axially of the element and is held in place by means operable to adjust the position of the magnet and thereby vary the force of its attraction on the ferro-magnetic clutch element when the faces of the elements are in contact.
- 20 4. The strand feeding means of claim 3, in which the magnet is mounted in an axial recess in its clutch element and is held by a bolt against a resilient seat in the recess and the bolt can be turned to change the position of the magnet in the recess.
- 25 5. The strand feeding means of claim 1, in which the feed roll includes a central part encircling the shaft and a removable sleeve enclosing the central part.
- 30 6. The strand feeding means of claim 5, in which the brake surface is carried by a ring attached to the sleeve.
- 35 7. The strand feeding means of claim 5, in which the separator is a roll of less diameter than the feed roll and mounted on an axis intersecting the axis of the feed roll and lying at an angle to both vertical and horizontal planes containing the axis of the feed roll, the separator is provided with a gear, and a ring gear on the removable sleeve meshes with the gear on the separator to drive the separator.
- 40 8. The strand feeding means of claim 1, in which the feed roll projects through an opening in a fixed shield and has a radial flange of greater diameter than the opening, the flange lying on the same side of the shield as the clutch elements, so that the shield limits the separation of the elements.
- 45 9. The strand feeding means of claim 8 in which a guide for the strand is mounted on the shield below the feed roll.
- 50 10. In a textile frame having a support for a package of a strand, the combination of a continuously rotating shaft, a clutch element mounted on the shaft for rotation therewith, a second clutch element loose on the shaft, the elements having faces adapted to be engaged with a non-slipping contact, a feed roll connected concentrically to the second element, a separator member mounted adjacent the feed roll, the feed roll and separator member cooperating to draw from the package a strand wound in a plurality of convolutions about the roll and member, means urging the elements together to cause the faces to
- 55
- 60
- 65
- 70
- 75

be engaged and the second element driven by the first, means for moving the elements apart including a brake shoe engageable with the second element to move it away from the first element, a lever operable to move the shoe into engagement with the second clutch element, and a spring urging the lever to operating position, and a stop motion including means for holding the lever inoperative and means held inactive by the unbroken strand and acting upon a strand break to put the holding means out of action and release the lever for movement to operating position by the spring.

11. The strand feeding means of claim 1, in which the member is urged by a spring to apply the brake shoe to the brake surface, the movement of the member by the spring is limited by an adjustable stop, and the member is held inoperative by means made effective by contact with the unbroken strand and acting to release the member when the strand breaks.

12. The strand feeding means of claim 8, in which the separator is a roll provided with a gear, a ring gear meshing with the gear on the separator is mounted on the flange on the feed roll, and the separator projects through an opening in the shield.
